METHOD OF COATING CANS AND ATTACH-
ING END MEMBERS THERETOJames H. O'Neil, Syracuse, N. Y., assignor to Con-
tinental Can Company, Inc., New York, N. Y., a
corporation of New York

Application November 1, 1937, Serial No. 172,302

2 Claims. (Cl. 113—120)

The invention relates generally to the art of forming metallic receptacles and has for an object to provide a novel method of coating cans and attaching end members thereto in a manner for assuring against the presentation of bare metal portions to contact with contained products.

It is customary to interiorly coat metallic containers adapted to receive certain products, so that direct contact between said products and the metal of the containers is avoided. This is particularly true in the canning of beer, since it has been found that the slightest exposure of the tin forming the outer surface of the metal causes a chemical reaction upon the beer sufficient to change its appearance, making it cloudy and unmarketable. The protective coating has been applied in various ways, as by dipping, flushing, or flooding the inside, outside, or both inside and outside of the can bodies in the coating solution, usually lacquer or enamel. An example of apparatus capable of coating can bodies by the dipping method is to be found in the application for Letters Patent filed by Alfred L. Kronquest, on April 12, 1937, Serial Number 136,473 now Patent Number 2,206,778. After the protective coatings are applied they are suitably hardened, as by baking.

Hardened coatings of the character stated are somewhat brittle, and when can ends are applied, and seamed securely in place, usually by a double roll seam, portions of the hard coatings are cracked or ruptured by the rolling of the seam, and as a result, bare metal surfaces are exposed to contact with products to be contained in the cans.

Seeking to remedy these faults, the invention resides in the novel method of coating cans and attaching end members thereto, which comprises the steps of interiorly coating the can bodies, air drying the coatings to a tacky state, applying end members, seam-securing said members in place while the coatings are tacky and including tacky coated portions in the seams, then baking the member equipped cans to harden said coatings and drive out volatile solvents contained in said seams.

With the above and other objects in view that will hereinafter appear, the nature of the invention will be more clearly understood by following

the description, the appended claims, and the several views illustrated in the accompanying drawing.

In the drawing:

Fig. 1 is a detail vertical section illustrating the 5 step of coating the can.

Fig. 2 is a detail vertical section illustrating the step of air drying the can.

Fig. 3 is an enlarged fragmentary section illustrating the step of seaming an end member in 10 place while the protective coating is in a tacky state.

Fig. 4 is a fragmentary diagrammatic section illustrating the step of baking the end member equipped can to harden the protective coating 15 and drive out volatile solvents confined within the end member securing seam.

In practicing the method, the can bodies 5 are coated interiorly, or both interiorly and exteriorly, by any approved method. As a single exemplification of the coating step I have shown, in Fig. 1 20 of the drawing, a portion of the Kronquest patent application apparatus hereinbefore referred to. The can bodies are supported on individual carriers 6 which are lowered and lifted by suitable mechanisms to immerse the cans in and remove 25 them from the protective coating bath 7. After the cans are coated internally and externally by this immersion they are attached to clips 8 depending from a conveyor chain 9 and are carried along in an air drying chamber.

This air drying step is illustrated in Fig. 2 of the drawing and may be carried on with or without forced circulation and in the presence of heat or without it as may be desired, the demands 35 of the invention being satisfied by any form of drying which will suitably bring the can coatings to a tacky state.

After the coating and the air drying steps have been completed an end member 10 is im- 40 mediately applied to the can body and seamed securely in place as indicated at 11 in Fig. 3 of the drawing. While the invention is not limited to the formation of a double roll seam this form of seam is commonly employed for this purpose 45 and is for that reason illustrated herein as an exemplification of the step of seam-securing an end member on a tacky, coated can. Any of the well known double seaming mechanisms may be employed in performing this step of the method 50

and an example of such mechanisms is to be found in the patent to A. L. Kronquest, issued April 1, 1930, as No. 1,752,912. In these mechanisms the double seam is formed by a chuck and successively operable first and second operation rollers. In Fig. 3 of the drawing I have shown only the chuck 12 and the second operation or seam completing roller 13.

Following the formation of the member securing seam, however formed, the can is placed in an oven to dry and harden the protective coating and drive out any volatile solvents confined within in the seam. The oven is diagrammatically illustrated at 14 in Fig. 4 of the drawing.

By applying and seam-securing the end members while the protective coating is in a tacky, plastic state, all danger of the coating cracking and chipping or flaking off and exposing the bare metal is avoided. The plasticity of the coating also aids somewhat in the formation of a perfect seal in the seam because of its ability to conform readily to the interstices between the seam components.

The end members referred to herein are, of course, the can bottom closures, the top end closures being attached after the cans have been filled at the brewery. During the draining off of the surplus protective coating material, as shown in Fig. 2, the can body end to which the bottom closure is to be applied is held uppermost. Due to the action of gravity, and the surface tension of the draining coating material, the applied coating film at the extreme upper end of the can body thins out to a considerable extent and, if allowed to harden, would become brittle

and inadequate as hereinbefore stated. The herein described method of attaching the bottom closures to the can body ends while the coatings are tacky overcomes the difficulties referred to. No such problems are presented at the lowermost or can top closure receiving ends because the coating material drains off in the direction of these ends, as shown in Fig. 2, and an adequate protective coating always is provided at said ends.

What I claim is:

1. The method consisting in coating the entire interior surface of a can body with a fluid coating, draining the superfluous fluid coating from the body while one coated end of the latter is uppermost, drying the remaining fluid coating to a tacky condition while said end is uppermost, and seam-securing a closure member coated on its interior face to said end of the body while the tacky condition of the can body coating persists, 20 including the rolling into the seam of part of said tackily coated end, and thereafter hardening the coating.

2. The method consisting in immersing a can body in a fluid coating, draining the superfluous fluid coating from the body while one end of the latter is uppermost, drying the remaining fluid coating to a tacky condition while said end is uppermost, double seam-securing a closure member coated on its interior face to said end 30 of the body while the tacky condition of the can body coating persists, including the rolling into the seam of part of said tackily coated end, and thereafter baking the coating.

JAMES H. O'NEIL. 35
